CLAIM

The ornamental design for an intraoral detector system, as shown and described.

DESCRIPTION

FIG. 1 is a top, rear, left perspective view of an intraoral detector system, showing my new design;

FIG. 2 is a bottom, rear, left perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is a top, front, left perspective view of FIG. 1, shown in an alternate configuration for clarity of disclosure.

The broken lines shown in the drawings show portions of the intraoral detector system that form no part of the claimed design.
